(57) **CLAIM**

The ornamental design for computer equipment, as shown and described.

DESCRIPTION

FIG. 1 is a front perspective view from above and one side of a computer equipment.

FIG. 2 is a rear perspective view from below and other side of a computer equipment.

FIG. 3 is a side view of computer equipment.

FIG. 4 is another side view of computer equipment.

FIG. 5 is a plan view of computer equipment.

FIG. 6 is an underneath plan view of computer equipment.

FIG. 7 is a front view of computer equipment; and,

FIG. 8 is a rear view of computer equipment.

The portions of the drawings shown in broken lines are for illustrative purposes only and form no part of the claimed design.

1 Claim, 4 Drawing Sheets

FIG. 1

FIG. 2

FIG. 3

FIG. 4

FIG. 5

FIG. 6

FIG. 7

FIG. 8
